UNITED STATES PATENT OFFICE.

GEORGE L. COLEMAN, OF DUBLIN, GEORGIA.

VARIABLE-SPEED DRIVE MECHANISM FOR COTTON-GINS.

1,259,081.

Specification of Letters Patent. Patented Mar. 12, 1918.

Application filed February 21, 1917. Serial No. 150,229.

To all whom it may concern:

Be it known that I, GEORGE L. COLEMAN, a citizen of the United States, residing at Dublin, in the county of Laurens, State of Georgia, have invented a new and useful Variable-Speed Drive Mechanism for Cotton-Gins; and I do hereby declare the following to be a full, clear, and exact description of the invention, such as will enable others skilled in the art to which it appertains to make and use the same.

This invention relates in general to variable speed drive mechanism and is a mechanism of this character for use on cotton-gins particularly.

Its principal object is to provide a driving means for a pair of conventional drums of a cotton-gin, so that the speed of one of the drums can be varied in respect with the other drum.

Another object is to provide means for stopping one of the drums irrespective of the other drum.

Another object is to provide a hand control for the speed variations that will enable the operator of the gin to quickly raise or lower the speed of one of the drums so as to give an even flow of cotton to the gin at all times, thereby increasing the capacity of the gin and giving a better sample of cotton.

The drawings do not aim at mechanical refinement in setting forth this invention, but alterations of the various associated parts may be permitted for the sake of more clearly applying the principles involved. Therefore, the right is reserved to reconstruct the device to meet the demands of practice, if such a reconstruction does not depart from the spirit of the appended claims.

In the drawings:—

Figure 1 is a side elevation of the invention, the casing for the worm and worm-gear being broken away to show them more clearly.

Fig. 2 is a top plan view, the worm-gear casing and side of the gin-feeder are shown in section.

Fig. 3 is an elevation of the hand lever for varying the speed of one of the drums.

Fig. 4 is a detail collective perspective view of the variable speed lever fork and the end of the worm-shaft.

Fig. 5 is a detail view of the cam sleeve for stopping the worm.

In the drawings 1 designates a conven-

tional cotton-gin feeder casing and mounted rotatably in said casing are drums 2 and 3. The shaft 4 carries the drum 2 and projects out of the casing 1 through the bearing 5 and carries on this extended end the worm gear 6 which is secured in place by the set screw 7 and key 8. A casing 9 is attached to 1 by appropriate screws 10. This casing incloses both the worm gear 6 and the worm 11. In the section 12 of this casing the worm 11 rotates, its shaft 13 having bearings in the opposite end walls thereof. The shaft 13 is provided with a spline 15 and is capable of a sliding motion through the worm 11, the feather 14, which is carried by the worm, secures the worm on the shaft against rotary movement thereon. At the end remote from the worm the shaft 13 carries the friction wheel 16 which is positively secured to it by any conventional means.

One end of the shaft 13 is provided with an annular groove in which the legs of fork 17 engage. This fork is pivotally connected at 18 with the lever 19 that is secured on the rock shaft 20 which has a pivotal mounting in the pillar block 21 and at the side of the casing 1. On the inner face of the pillar block a rack 22 is secured over whose teeth 23 the arm 24 moves. The arm 24 is positively connected with the rock shaft 20 and, as the lever 19 is moved, the arm moves over the teeth 23 and engages between any two teeth to hold the lever 19 in the desired position.

The pillar block 21 is an integral part of the base 22^a which extends from the feeder casing. This block has a bearing for the shaft 23^a for which there is also a bearing 24^a secured to the side of the casing 1. The spiked drum 3 is secured on the shaft inside the casing 1 and is rotated when motion is transmitted to the grooved wheel 25. The wheel 25 has a long hub 26 through the instrumentality of which it is permitted to slide longitudinally on the shaft 23. The feather 27 which slides in the spline 28 prevents rotary movement of the wheel 25 in respect to the shaft 23.

The bearing 24^a has the end cut off at an angle and the shaft 23 carries a movable sleeve 29 with the end similarly angled off, the end of the sleeve and the end of the bearing adjoining each other at these angled ends. A handle 30 is integrally connected with the sleeve 29 as are also two lugs 31

between which the latch 32 is designated to fall. This latch is riveted between the lugs 33 integrally attached to the bearing 24. Just inside of the pillar block 21 a collar 34 is secured to the shaft 23 and between this collar and the grooved wheel or pulley 25 a spiral spring 35 is under compression. This spring holds the inner face of the pulley or wheel 25 in contact with the edge of the friction wheel 16, so that, when the pulley or wheel 25 is rotated the friction wheel 16 will rotate in consequence.

The sleeve 29 provides a means for moving the pulley 25 out of contact with the friction wheel 16. When the latch 32 is raised the sleeve 29 may be turned by its handle 30, its angled end and the angled end of the bearing 24 coöperating to move the pulley 25 longitudinally on the shaft 23 against the pressure of the spring 35. When the friction wheel 16 rotates (as it will when in contact with the pulley 25) the worm 11 is rotated as a result of which the worm wheel 6 and the drum 2 are also rotated. The speed of the worm and consequently the speed of the drum 2 can be varied by operating the lever 19, the pivoted fork 17 of which operates to move the shaft 13 longitudinally through the worm 11. The friction wheel 16 being secured to the shaft 13 moves with it and is brought toward the center or toward the periphery of the pulley 25, which will make its speed slow or fast with respect to pulley 25 depending on whether it is near the center or near the circumference thereof.

What is claimed is:

1. In a variable speed mechanism, a driving shaft, a grooved pulley splined thereon, bearings for the ends of said shaft, one of said bearings having an angled end, a sleeve on the shaft and having an angled end to co-operate with the first angled end and interposed between the first angled end and the hub of the pulley, a latch connection between the sleeve and the angled end bearing said sleeve having a handle, whereby it may be rocked when the latch is disconnected to move the pulley longitudinally on said shaft, thereby disengaging said pulley from contact with a friction wheel, a spring against the action of which said pulley is moved, a driven shaft having a worm wheel and being arranged in parallelism with the driving shaft, a shaft at right angles to the driving and driven shafts and having a worm meshing with said worm wheel, and a friction wheel carried by said last named shaft, whereby its peripheral edge may frictionally contact with one face of said pulley.
2. In a variable speed mechanism, a driving shaft, a grooved pulley splined thereon, bearings for the ends of said shaft, one of said bearings having an angled end, a sleeve on the shaft and having an angled end to co-operate with the first angled end and inter-

posed between the first angled end and the hub of the pulley, a latch connection between the sleeve and the angled end bearing said sleeve having a handle, whereby it may be rocked when the latch is disconnected to move the pulley longitudinally on said shaft, thereby disengaging said pulley from contact with a friction wheel, a spring against the action of which said pulley is moved, a driven shaft having a worm wheel and being arranged in parallelism with the driving shaft, a shaft at right angles to the driving and driven shafts, a worm through which said last named shaft slidably telescopes and splined therein, and a friction wheel carried by the last named shaft whereby its periphery may frictionally contact with one face of said pulley, and means for moving said last named shaft through the worm, for adjusting the periphery of the friction wheel with respect to the center of said pulley, whereby said driven shaft may be rotated at variable speeds.

3. In a variable speed mechanism, driving and driven shafts in parallelism to each other, the driving shaft having a grooved pulley to which power may be transmitted, a worm wheel on the driven shaft, a shaft to one side of and at right angles to the driven shaft and having a friction wheel at one end, whereby its periphery may frictionally contact with one face of said pulley, a worm meshing with said worm wheel and being splined to the last named shaft, whereby said last mentioned shaft may move longitudinally and axially therethrough, a support, bearings in which said support is rockably mounted, said support having a right angled extending arm, means to be engaged by said arm to hold the support in different adjusted positions when rocked, a lever movable with said support a member pivoted on said lever and having a loose connection with one end of said last mentioned shaft, whereby as said lever is moved and the support rocked said last mentioned shaft may be moved axially through its worm for adjusting the periphery of the friction wheel toward and from the center of said pulley, whereby the driven shaft may be rotated at variable speeds.

4. In a variable speed mechanism, driving and driven shafts in parallelism to each other, the driving shaft having a grooved pulley to which power may be transmitted, a worm wheel on the driven shaft, a shaft to one side of and at right angles to the driven shaft and having a friction wheel at one end, whereby its periphery may frictionally contact with one face of said pulley, a worm meshing with said worm wheel and being splined to the last named shaft, whereby said last mentioned shaft may move longitudinally and axially therethrough, a support, bearings in which said support is rockably

mounted, said support having a right angled extending arm, means to be engaged by said arm to hold the support in different adjusted positions when rocked, a lever movable with
5 said support, a member pivoted on said lever and having a loose connection with one end of said last mentioned shaft, whereby as said lever is moved and the support rocked said last mentioned shaft may be moved
10 axially through its form for adjusting the periphery of the friction wheel toward and from the center of said pulley, whereby the

driven shaft may be rotated at variable speeds, and means for moving the pulley toward and from the periphery of the friction 15 wheel.

In testimony whereof I have signed my name to this specification in the presence of two subscribing witnesses.

GEORGE L. COLEMAN.
